UNITED STATES PATENT OFFICE.

SHELDON JOSEPH, OF WHEELING, WEST VIRGINIA, ASSIGNOR OF EIGHTEEN ONE-HUNDREDTHS TO J. PLUMER COLE, SIXTEEN ONE-HUNDREDTHS TO WILLIAM B. CASEY, AND SIXTEEN ONE-HUNDREDTHS TO ELMER H. MEAGLE, ALL OF WHEELING, WEST VIRGINIA.

KEROSENE-GAS GENERATOR AND BURNER USING RADIANTS.

Application filed February 6, 1926. Serial No. 86,613.

The object of my invention is to provide a kerosene gas generator and burner using radiants of improved construction having a minimum of parts. I attain the object of 5 my invention by the mechanism illustrated in the accompanying drawings, in which—

Figure 1 is a side elevation of my invention;

Fig. 2 is a horizontal section on line 2—2 10 of Fig. 1;

Fig. 3 is a transverse section on line 3—3 of Fig. 1; and

Fig. 4 is a detail sectional view on line 4—4 of Fig. 1.

15 Like characters of reference indicate like parts in each of the several views.

Referring to the accompanying drawings, I provide a fuel tank 1 out of which opens the fuel supply pipe 3 controlled by valve 2; the pipe 3 opens into the head 4 of the valve housing 5 which terminates in a reduced end 6 and outlet passage 7. I provide a cylindrical rod 8 having a threaded stem 10 screw threaded into the housing head 4 and operable by means of hand wheel 11. The rod is of smaller diameter than the chamber of valve housing 5 leaving the annular space 15, as shown in Fig. 2. Rod 8 is provided with a reduced end 9 tapered at 20 the end to form a valve seated on the outlet 7. I provide an air chamber 37 extending from outlet 7 to the main burner 31. Main burner 31 carries the gas mantles or radiants 36.

35 I provide a series of ports 32 in the main burner 31 over which the gas mantles or radiants are seated and I also provide a suitable damper 33 for opening and closing the ports 32. I provide a lateral longitudinal extension 34 to the burner 31 having heating ports 35 as shown in Fig. 3.

Referring to Fig. 2, I provide an outlet 12 from chamber 15 to the passage 18 in a second tube 17, which passage is provided 45 with a valve seat 19 adapted to be controlled by the valve 20 which is operated by hand wheel 21. Valve 20 functions to shut off the oil from the inlet pipe 12, keeping it out of the passage 18. I provide a suitable packing gland 22 in which the stem of the valve 21 is mounted. I provide a similar packing gland 14 in which the stem of valve 11 is mounted. I also provide a packing gland

38 similar to glands 22 and 14. At the other end of passage 18 I provide a cap or closure 23 from which a tube or connecting pipe 24 extends to valve casing 25 in which casing is mounted the needle valve 26 which is controlled by the hand wheel 27. A suitable air passage 28 extends from valve casing 25 to burner 29. Under burner 29 is a suitable pan 30.

In operation the tank 1 is partially filled with kerosene oil and the remaining space is filled with air under pressure. When the 65 valve 2 is opened the oil flows through pipe 3 into the valve housing 4 where it is heated and the vaporized oil thence flows, mingled with air, through the chamber 16, outlet 7 and passage 37 to the main burner 31. 70 The burner 29 which is positioned under and between the valve housing 5 and burner 29 operates to heat both tubes 17 and 5. Both members 17 and 5 function as gas generators, while member 29 functions as a 75 Bunsen burner. The auxiliary burner may be kept burning when the ports 32 are closed by the damper 33. When port 7 is closed burner 29 continues to keep tubes 5 and 17 hot so that mantles 36 may be lighted at any 80 time.

What I claim is:

1. In a kerosene or coal oil burner, the combination of a gas manifold having gas radiants, means for regulating the flow of 85 gas to the radiants, a valve controlled gas generator in communication with the gas manifold, said generator including a tubular casing, a cylinder of smaller diameter than the casing and terminating in a needle 90 valve, a chamber having a passage in which the needle valve seats, said passage opening into the manifold leading to the gas radiants, means for supplying coil oil under pressure to the generator, a Bunsen burner 95 arranged in proximity to the generator and positioned under and at one side of said generator and a valve controlled pipe connection between the Bunsen burner and the generator.

2. In a kerosene or coal oil burner, the combination of a gas manifold having gas radiants, means for regulating the flow of 100 gas to the radiants, a valve controlled gas generator in communication with the gas 105 manifold, a valve controlled auxiliary gen-

erator, and a Bunsen burner disposed in a horizontal plane under and in a vertical plane between the aforesaid generators and adapted to heat both of them.

- 5 3. In a kerosene or coal oil burner, the combination of a gas manifold having gas radiants, means for regulating the flow of gas to the radiants, a valve controlled gas generator in communication with the gas manifold, a valve controlled auxiliary generator, a Bunsen burner disposed in a horizontal plane under and in a vertical plane between the aforesaid generators and adapted to heat both of them, valve controlled 10 means for supplying fuel under pressure to the generator and valve controlled means for allowing fuel to flow from one generator to the other generator.

4. In a kerosene or coal oil burner, the combination of a gas manifold having gas radiants, a valve controlled generator in communication with the gas manifold, said generator comprising a cylindrical chamber, a cylinder mounted in said chamber, said 20 cylinder having a needle valve at one end thereof and an operating stem at the other end thereof, a valve passage from the generator chamber to the gas manifold, a valve controlled auxiliary generator in communication with the first mentioned generator, a Bunsen burner arranged to heat both of the aforesaid generators, and means for supplying fuel to one of the generators.

5. In a kerosene or oil burner, the combination of a gas manifold having gas radiants, means for regulating the flow of gas to the radiants, a valve controlled gas generator in communication with the gas manifold, said generator including a tubular casing, a cylinder of smaller diameter than the casting and terminating in a needle valve, a damper chamber having a passage into which the needle valve seats, said passage opening into the manifold leading to the gas radiants, means for supplying coal oil under pressure to the generator, a Bunsen burner arranged in proximity to the generator and positioned under and at one side of said generator, a valve controlled pipe connection 40 between the Bunsen burner and the generator, and a damper slidably mounted on the gas manifold and adapted to shut off the flow of gas to the gas radiants at will while permitting of its continued flow to the generator.

6. In a kerosene or oil burner, the combination of a gas manifold having gas radiants, means for regulating the flow of gas to the radiants, a valve controlled gas generator in communication with the gas manifold, a valve controlled auxiliary generator, a Bunsen burner disposed in a horizontal plane under and in a vertical plane between the aforesaid generators and adapted to heat both of them, and a damper slidably mounted on the gas manifold to permit of closing or partly closing the main burner ports while permitting of continuous heating of the gas generator.

7. In a kerosene or oil burner, the combination of a gas manifold having gas radiants, means for regulating the flow of gas to the radiants, a valve controlled gas generator in communication with the gas manifold, a valve controlled auxiliary generator, a Bunsen burner disposed in a horizontal plane under and in a vertical plane between the aforesaid generators and adapted to heat both of them, and a damper slidably mounted on the gas manifold to permit of closing or partly closing the main burner ports while permitting of continuous heating of the gas generator, and valve controlled means for supplying fuel under pressure to the generator and valve controlled means for allowing fuel to flow from one generator to the other generator.

8. In a kerosene or oil burner, the combination of a gas manifold having gas radiants, a valve controlled generator in communication with the gas manifold, said generator comprising a cylindrical chamber, a cylinder mounted in said chamber, said cylinder having a needle valve at one end thereof and an operating stem at the other end thereof, a valve passage from the generator chamber to the gas manifold, a valve controlled auxiliary generator in communication with the first mentioned generator, a Bunsen burner arranged to heat both of the aforesaid generators, means for supplying fuel to one of the generators, and a damper slidably mounted in the gas manifold under the gas radiants to permit of closing or partly closing the main burner ports and leaving the auxiliary burner ports free to burn with a greater pressure to assist in keeping the generator tube hot for instant service.

SHELDON JOSEPH.
